L. N. HILLS

FRUIT JUICE SEPARATOR

Filed Feb. 6, 1922

Louis N. Hills
INVENTOR
BY *Victor J. Evans*
ATTORNEY

UNITED STATES PATENT OFFICE.

LOUIS N. HILLS, OF HAYBRO, COLORADO.

FRUIT-JUICE SEPARATOR.

Application filed February 6, 1922. Serial No. 534,482.

To all whom it may concern:

Be it known that I, LOUIS N. HILLS, a citizen of the United States, residing at Haybro, in the county of Routt and State of Colorado, have invented new and useful Improvements in Fruit-Juice Separators, of which the following is a specification.

This invention relates to a fruit juice, pulp and seed separator and has for its primary object the construction and association of parts whereby the above elements may be separated by centrifugal action.

An object of the invention is the provision of removable screens so that fruit of different size may be separated and properly taken care of.

A feature of my invention is the novel manner of constructing and supporting the inner cylinder and arranging the wire screen therein in such manner that the same will not become dislocated.

With these and other objects in view the invention will be better understood from the following detailed description taken in connection with the accompanying drawing wherein:

Fig. 1 is a vertical sectional view of the apparatus.

Fig. 2 is a sectional view on the line 2—2 of Fig. 1.

Fig. 3 is a detail view of a portion of a screen of a larger mesh than the screen shown in Fig. 1.

Again referring to the drawing illustrating one of the many constructions of my invention the numeral 1 designates a casing to which is attached the clamps 2 by means of which the casing may be secured in place. This casing encloses the drive mechanism 3 consisting of a main shaft 4 supported by the crank arm 5 and to which is secured the main drive gear 6. It is of course to be understood that the main shaft may be power driven. This gear 6 meshes with a small gear 7 on the intermediate shaft 8. This intermediate shaft 8 has mounted thereon a worm wheel 9 engaging a worm 10 of the proper pitch to be operated by the worm wheel 9. This worm 10 is formed on a vertical shaft 11 that is provided with a foot bearing 12.

The numeral 13 designates an outer cylinder forming a portion of and projecting above the casing 1. This cylinder 13 is pro-

vided with an outlet 14. The inner cylinder 55 15 is easily removed from the upper end of the shaft to facilitate cleaning. The peripheral surface of the cylinder is provided with a series of slots 17 which may be of any number and size. 60

The numeral 18 designates a removable screen arranged within the cylinder and completely closing the slots.

A very important feature of my invention is that two or more screens will be provided 65 of different mesh so that juices of different consistency may be properly taken care of. These screens are held against accidental displacement in a novel manner now to be described. 70

A cover 19 is provided with an outer flange 20 engaging the outer cylinder and is further provided with an inner flange 21 encircling the upper part of the inner cylinder to cooperate with the shaft to accommodate 75 proper rotation of the inner cylinder. It will also be noted that the cover is so arranged with relation to the screen that the same cannot rise vertically and become displaced. To complete the invention I provide the knob 22 for moving the cover.

From the foregoing description taken in connection with the accompanying drawing it will be apparent that I provide an apparatus that is of simple, substantial construction that will positively remove juices by centrifugal action and allow same to pass from the outlet 14 into a suitable receptacle. By the use of removable screens of different mesh I can accomplish the foregoing in a most efficient manner possible.

It is, of course, to be understood that the invention may be constructed in various other manners and the parts associated in different relations and, therefore, I do not 95 desire to be limited in any manner except as set forth in the claim hereunto appended.

Having thus described my invention what I claim is:

A juice separator comprising a casing, an 100 outer cylinder upstanding therefrom, drive mechanism mounted in the casing including a crank handle arranged exteriorly of the casing, a vertical shaft having connection with said drive mechanism, an inner cylinder 105 mounted within the outer cylinder and supported for rotation by said shaft, said inner cylinder having its walls arranged in equal

spaced relation with the outer cylinder and provided with a plurality of longitudinal slots arranged circumferentially thereof and disposed in alignment above and below the 5 horizontal center of the cylinder, a removable screen supported by the inner cylinder, a cover for the outer cylinder having de-

pending flanges arranged in spaced relation with the outer flange engaging the inner wall of the outer cylinder and the inner 10 flange engaging the outer wall of the inner cylinder.

In testimony whereof I affix my signature.
LOUIS N. HILLS.
